SELF-CLEANING DOOR MAT

Carl O. Swanson, Minneapolis, Minn.

Application November 30, 1944, Serial No. 565,873

8 Claims. (Cl. 15—97)

1

This invention relates to door mats, and the main object is to provide a novel, efficient and practical construction of door mat including mechanically moving and power actuated elements which are operative to automatically scrape and clean the soles of shoes worn by people entering the building in which the mat apparatus has been installed.

The invention is particularly intended and designed for use in office buildings, hospitals, stores, banks, churches, theaters, and similar buildings, patronized by the general public. In such buildings, as is well known, the amount of mud, slush, and dirt carried into and deposited on the floor by pedestrians, particularly in rainy and snowy weather, is substantial, and not only results in unsightly soiling and wear of the floor surface but is very unsanitary, often produces a dangerously slippery condition, and of course frequently results in soiling fixtures, walls, furniture and merchandise, all of which requires labor and expense to keep clean.

To overcome these and other objections I provide a door mat having a series of endless belts over which the people walk and the apparatus is installed in the floor immediately inside the outer building door so that the building patrons are compelled to traverse it as they enter; and, in wet or slushy weather these belts are set in motion, by suitable applications of power, to produce a scrubbing action on the shoes or rubbers of those passing over. As further features of the invention I provide the mat with fixed grill bars, between the belts, and upon which the pedestrian's weight is primarily borne; and a receptacle through which the lower runs of the belts are operated so as to deposit dirt therein and be washed by water or other cleansing solution in the receptacle.

Still other and more detailed features and characteristics of the invention will be disclosed in the course of the following specification, reference being had to the accompanying drawings, wherein:

Fig. 1 is a plan view of the door mat showing it as installed in a floor inside a revolving door, the latter and its adjacent wall portions being shown in section.

Fig. 2 is an enlarged sectional elevation on the line 2—2 as in Fig. 1.

Fig. 3 is a cross sectional elevation on line 3—3 in either Fig. 1 or Fig. 2.

Fig. 4 is a longitudinal sectional elevation through a modified form of the apparatus.

2

Fig. 5 is a cross sectional elevation on line 5—5 in Fig. 4.

Referring to the drawings more particularly and by reference characters A designates the 5 ground floor of a building having a front wall B provided with a revolving door entrance C, as shown in Fig. 1. Immediately inside the entrance C the floor is provided with a rectangular inset frame structure 6 which supports a housing or pan 7 which depends below the floor surface. Extending longitudinally with respect to the general path of foot travel the frame 6—7 includes a series of transversely spaced, parallel bars 8, disposed in vertical planes and secured 10 at their ends in the frame, the upper edges of these bars being flush with the floor surface and adapted to engage the feed and support the weight of pedestrians passing in from the door, it being understood that these bars are rigid and 15 stationary in the frame.

Intermediate the bars 8 is a series of flexible belts 9, which are stretched over rollers 10 at opposite ends of the frame, and since the belts are 20 of flexible and preferably elastic material, such as rubber, it will be seen that they will be substantially taut as they travel between the bars. The upper surfaces of these belts are preferably disposed slightly below the levels of the upper 25 edges of the bars 8, but are provided with tapered cleats 11 which normally project above the floor level of the bar edges so as to yieldably contact with and thus brush off or clean the sole surfaces of footwear worn by the pedestrians as 30 they walk over this area of the floor.

The rollers 10 are mounted on a pair of shafts 12 and 13, one at each end of the receptacle 7, and the shaft 12 extends from the receptacle to be driven by a shaft 14 through a pair of bevel pinions 15. The shaft 14 is rotated by a motor or 35 other suitable source of power (not shown) and which is started and stopped as weather conditions may require.

Extending both lengthwise and transversely under the upper runs of all the belts 9 is a plate 45 16, the same being preferably supported by a series of end lugs 17 which engage the shafts 12 and 13 intermediate the belts. The lugs 17 which trunnion on the shaft 13 may extend from a 50 separate cross piece 18 adjustably secured to the plate 16 by bolts 19 so that the spacing between the shafts may be slightly adjusted to thereby regulate the tension of the belts as wear and slack may develop.

The plate 16 serves a further and more important purpose, however, and that is to provide

yieldable support for the belts throughout their respective spans between the rollers, and this is accomplished by attaching to the plate series of spring bumpers or fingers 20, as shown in Fig. 2, which are firmly attached at their lower and leading ends to the plate while their upper and trailing ends are arched to slidably engage the under surfaces of the upper runs of the belts. With this construction it will be evident that the belt cleats 11 will always and at all points be held up in effective wiping contact with the bottom surfaces of the footwear worn by pedestrians, but that the entire construction will have sufficient flexibility so that the person's weight will cause his feet to remain in frictional contact with the upper edges of the bars 8 and thus prevent him from being moved or thrown off balance by the travel action of the belts.

To render the cleaning action of the belts more effective I cause the lower runs of the belts 9 to travel in a bath of water or other cleaning fluid which is contained in the receptacle 7, and to provide for the necessary supply and circulation of the fluid I have shown a supply or inlet pipe 21 at one end of the receptacle, while an outlet pipe 22 is preferably located at the other end and may also serve as an overflow drain to maintain a predetermined level of the fluid in the receptacle.

At the right hand end of the device, as shown in Fig. 2, I provide a series of wiper springs 23, one for each belt. One end of the spring is anchored, as at 24, to the frame, while the opposite end edge is held in yielding contact with the belt. The intermediate part of the spring is curved in such a manner that it will yield and cause the free end of the spring to engage the belt surface with a wiping contact as it moves upwardly from the liquid bath about the adjacent roller 10, such contact also being of such nature that it will remove surplus moisture from the belts 11.

The operation of the device as thus set forth will no doubt be obvious, but may be summarized as follows: Under dry or fairly normal weather conditions the device merely serves as an ordinary or conventional door mat, and people entering the building may wipe their feet on it as they pass over in the usual manner. Any dust or dirt so deposited will escape downwardly between the belts 9 and bars 8, to be received in the pan 7.

When weather conditions are wet or snowy power is applied to the shaft 14 and water is admitted into the pan through pipe 21. It is preferable to have the water flow continuously, and as it then escapes through the overflow drain 22 it carries with it much of the dirt, and the continued flow of clean water along the belts tends to wash the belts and keep them clean. It will be noted that this action is facilitated by the fact that the water moves along the pan in a direction opposite to the direction in which the lower or submerged run of the belt is operating. As the belts now emerge from their bath they are wiped off by the spring wipers 23.

The upper runs of the belts, together with their projecting lugs, then move along between the upper edges of the bars 8, and when a person steps on the mat the springs 20 will yield sufficiently so that his weight is imposed and carried directly upon the bars. During the period or interval while the foot remains in this position the belt lugs produce a wiping action on the shoe and after the person has taken the few steps necessary to cross the mat his foot wear will be

wiped substantially clean of all surplus and objectionable dirt, slush, and moisture, after which he proceeds on his way into the building with comparatively dry and clean feet.

Turning now to the modification shown in Figs. 5 and 6, it will be noted that the pan 25 has a fluid inlet at 26, an outlet at 27, and intermediate these points is provided with an inclined bottom terminating in a trap 28 through which dirt and other sediment may be discharged. In this case, too, the shaft 29 supporting one set of rollers 30 is driven through bevel pinions 31 by a motor 32 disposed adjacent thereto in a chamber 33 formed at one end of the housing or frame structure. The opposite shaft 34 extends through slots in the bars and in the side walls in the casing for bearing engagement in bearings 35 which are adjustable at 36 to take up slack in the belts.

The belts 37 in this instance are provided with brush bristles or tufts 38, instead of the lugs 11 as shown in Figs. 2-3, and these bristles are sufficiently flexible so that they will yield and vigorously brush off the pedestrians' shoes. With this arrangement it is not necessary to provide yielding support (such as springs 20) for the belts proper and for that reason I permit the belts to travel in fixed or rigid channels 39. These channels are formed by the upper edge portions of the bars 8 and horizontal intermediate bars or plates 40 the edges of which are welded or otherwise secured to the bars 8. Thus the plates 40 not only support the belts but tend to rigidify the entire frame construction.

It will be understood that still further modifications may be made in the invention without departing from the spirit and scope of the appended claims. Having now therefore fully illustrated and described preferred embodiments of the invention, what I claim to be new and desire to protect by Letters Patent is:

1. A self-cleaning door mat comprising a frame set in a floor substantially flush with the surface thereof, said frame comprising spaced, parallel, pedestrian supporting bars, a series of endless power actuated belts stretched over rollers below the floor surface and having their upper runs extending between said bars, said belts having integrally formed lugs adapted to project above the level of the upper edges of the bars to clean pedestrian shoes, a receptacle under and substantially coextensive with the length of the frame, fluid supply means to the receptacle for washing the belts and lugs as the belts travel their under runs between said rollers, and means for wiping surfaces of the belts and lugs after they have been washed and before they return to shoe cleaning elevation.

2. A self-cleaning door mat comprising a frame set in a floor substantially flush with the surface thereof, said frame comprising spaced parallel, pedestrian supporting bars, a series of endless power actuated belts stretched over rollers below the floor surface and having their upper runs extending between said bars, said belts having integrally formed lugs adapted to project above the level of the upper edges of the bars to clean pedestrian shoes, a receptacle under and substantially coextensive with the length of the frame, fluid supply means to the receptacle for washing the belts and lugs as the belts travel their under runs between said rollers, and means for wiping surfaces of the belts and lugs after they have been washed and before they return to shoe cleaning elevation, said wiping

means comprising a series of flexible devices rigidly mounted with respect to the frame and having yieldable contact with the respective belts to remove foreign material from the surfaces thereof and from the lugs thereon as the belts move therepast.

3. In a self-cleaning door mat, a series of spaced, parallel bars mounted substantially flush with the surface of a floor to support pedestrians walking thereover, a series of power actuated endless belts mounted on rollers below opposite ends of the bars and with their upper runs extending horizontally between the bars, shoe scraping lugs extending from the outer surfaces of the belts, a fluid receptacle disposed below the bars and extending horizontally and substantially coextensively therewith whereby the entire lower runs of the belts between the rollers may travel in a fluid bath in the receptacle and thereby loosen foreign matter adhering to the belt and lug surfaces, and means for removing bath fluid from the exposed belt and lug surfaces before they are returned to the upper shoe cleaning run of travel.

4. In a self-cleaning door mat, a series of spaced, parallel bars mounted substantially flush with the surface of a floor to support pedestrians walking thereover, a series of power actuated endless belts mounted on rollers below opposite ends of the bars and with their upper runs extending horizontally between the bars, shoe scraping lugs extending from the outer surfaces of the belts, a fluid receptacle disposed below the bars and extending horizontally and substantially coextensively therewith whereby the entire lower runs of the belts between the rollers may travel in a fluid bath in the receptacle and thereby loosen foreign matter adhering to the belt and lug surfaces, and means for removing bath fluid from the exposed belt and lug surfaces before they are returned to the upper shoe cleaning run of travel, said receptacle being provided with fluid supply and outlet means operative to maintain a fluid supply of constant level whereby the lower runs of the belts will travel at a predetermined depth in the fluid bath.

5. In a self-cleaning floor mat, a series of spaced, parallel bars rigidly mounted in a floor with their upper edges substantially flush with the floor surface, a series of power actuated endless belts mounted on end rollers below the floor surface and with their upper runs extending longitudinally between the bars, shoe scraping lugs extending from the outer surfaces of the belts and so formed as to normally project above the level of the top edges of the bars, and means in substantially coextensive supporting contact with the upper run of each belt, such means being yieldable under direct foot pressure on the belt lugs under the area of greatest foot pressure while permitting other parts of the supporting means to also maintain the belt lugs in cleaning contact with shoe surfaces slightly above the upper bar edges.

6. In a self-cleaning floor mat, a series of spaced parallel bars rigidly mounted in a floor with their upper edges substantially flush with the floor surface, a series of power actuated endless belts mounted on end rollers below the floor

surface and with their upper runs extending longitudinally between the bars, shoe scraping lugs extending from the outer surfaces of the belts and so formed as to normally project above the level of the top edges of the bars, and means for yieldably supporting the upper runs of each belt, said supporting means being substantially coextensive with the shoe engaging length of the belt, and being yieldable as to any given belt length pressure area without yielding as to remaining belt length areas.

7. In a self-cleaning floor mat, a series of spaced, parallel bars rigidly mounted in a floor with their upper edges substantially flush with the floor surface, a series of power actuated endless belts mounted on end rollers below the floor surface and with their upper runs extending longitudinally between the bars, shoe scraping lugs extending from the outer surfaces of the belts and so formed as to normally project above the level of the top edges of the bars, and means including a series of pressure responsive supporting devices extending under and throughout the upper run of each belt and being operative to hold all belt lugs above the top level of the bars except where foot pressure at a given area is sufficient to press the belts down to a lug level corresponding to that of the upper edges of the bars.

8. In a self-cleaning floor mat, a series of spaced, parallel bars rigidly mounted in a floor with their upper edges substantially flush with the floor surface, a series of power actuated endless belts mounted on end rollers below the floor surface and with their upper runs extending longitudinally between the bars, shoe scraping lugs extending from the outer surfaces of the belts and so formed as to normally project above the level of the top edges of the bars, and means in substantially coextensive supporting contact with the upper run of each belt, such means being yieldable under direct foot pressure on the belt lugs under the area of greatest foot pressure while permitting other parts of the supporting means to also maintain the belt lugs in cleaning contact with shoe surfaces slightly above the upper bar edges, said supporting means for each belt being operative independently of the supporting means for the other belts.
